Specification for Design.

Patented June 18, 1912.

Application filed March 12, 1912. Serial No. 683,346. Term of patent 3½ years.

To all whom it may concern:

Be it known that I, JOHN C. WACHA, a subject of the Emperor of Austria-Hungary, residing at Providence, in the county of Providence and State of Rhode Island, have invented a certain new, original, and ornamental Design for a Display-Stand for Jewelry, of which the following is a specification.

In the accompanying drawing which

forms a part of this specification, the figure is a perspective view of a display stand for jewelry embodying my new design.

I claim:

The ornamental design for a display stand for jewelry, as shown.

JOHN C. WACHA.
